CLAIM

The ornamental design for a shoe sole, as shown and described.

DESCRIPTION

FIG. 1 is a perspective view of a shoe sole showing my new design; and,

FIG. 2 is a plan view of the shoe sole as shown in FIG. 1. The uneven broken line immediately adjacent to the shaded area represents the bounds of the claimed design. All other uneven broken lines outside of the uneven broken line immediately adjacent to the shaded area represent the remaining portion of the shoe. The uneven broken lines within the shaded area are for the purpose of illustration and form no part of the claimed design. The uneven broken line representations in FIGS. 1-2 are for illustrative purposes only and form no part of the claimed design.
